(57) **CLAIM**

The ornamental design for a parallel active optical cable, as shown and described.

DESCRIPTION

FIG. 1 is a top perspective view of a first embodiment of a parallel active optical cable, showing our new design;

FIG. 2 is a top view thereof;

FIG. 3 is a left side view thereof;

FIG. 4 is a right side view thereof;

FIG. 5 is a front view thereof;

FIG. 6 is a rear view thereof;

FIG. 7 is a bottom view thereof;

FIG. 8 is a top perspective view of a second embodiment of a parallel active optical cable, showing our new design;

FIG. 9 is a top view thereof;

FIG. 10 is a left side view thereof;

FIG. 11 is a right side view thereof;

FIG. 12 is a front view thereof;

FIG. 13 is a rear view thereof;

FIG. 14 is a bottom view thereof;

FIG. 15 is a top perspective view of a third embodiment of a parallel active optical cable, showing our new design;

FIG. 16 is a top view thereof;

FIG. 17 is a left side view thereof;

FIG. 18 is a right side view thereof;

FIG. 19 is a front view thereof;

FIG. 20 is a rear view thereof; and,

FIG. 21 is a bottom view thereof.

The broken line in the figure drawings is included for the purpose of illustrating unclaimed environment and forms no part of the claimed design.

See application file for complete search history.
